CONTRACTION JOINT

John N. Heltzel, Warren, Ohio

Application May 7, 1927. Serial No. 189,543

4 Claims. (Cl. 94—17)

The present invention relates to contraction joints for concrete roads and pavements, and aims to provide novel means for producing and controlling the breaking of the concrete along a straight or predetermined line in a manner to have the advantages of a natural break without the disadvantage of the irregular line of a natural break.

It has been the practice in building concrete roads and pavements to permit the transverse contraction cracks to develop naturally, as the concrete dries out and the same contracts. This has the advantage of causing irregular interlocking surfaces on the sections or slabs, with protruding stones, pebbles or gravel entering recesses in the confronting surfaces of the adjacent slabs, so as to prevent relative vertical displacement of the slabs. The natural breaks have the disadvantage, however, of occurring at irregular points along the road and extending along irregular lines across the road.

The present invention aims to provide means for controlling the breaks along definite lines at the surface of the concrete, with the slabs interlocked between the surface and sub-base similar to that which occurs with a natural break, in order that the break at the surface of the concrete will extend along a straight or regular line, whereas the break below the surface will be irregular, similar to a natural break. The breaking of the concrete is thus controlled to provide slabs of predetermined proportions, with a neat appearance of the breaks at the surface of the concrete, and the adjacent surfaces of the slabs interengaged to prevent relative vertical displacement thereof.

With the foregoing and other objects in view, which will be apparent as the invention is more fully understood, the invention resides in the construction and arrangement of parts as hereinafter described and claimed, it being understood that changes can be made within the scope of what is claimed without departing from the spirit of the invention.

The invention is illustrated in the accompanying drawing, wherein—

Figure 1 is a perspective view illustrating longitudinal and transverse joints of a concrete road, embodying the improvements.

Fig. 2 is a cross section of one of the joints.

Fig. 3 is a fragmentary perspective view illustrating a modification.

In carrying out the invention there are provided division strips 7, as seen in Figs. 1 and 2, of sheet metal, fibre, or other suitable material,

which are embedded in the concrete to define the lines of breaks thereof. As shown, the strips are employed for both the longitudinal and transverse breaks or joints, although they are especially intended for the transverse contraction joints. The strips 7 are of a width to extend from the surface of the concrete part way down, with their lower edges spaced above the sub-base, so that the division strips or plates do not divide the concrete completely.

The strips 7 have portions or pockets 8 pressed to opposite sides and forming protuberances with recesses or cavities at the opposite sides. These portions 8 are preferably of irregular form and arrangement, and are of pyramidal or similar shape, to represent or simulate broken stone, such as used as aggregate in road construction. Each portion 8 has an aperture 9 at its apex, to permit the air to escape from the cavities, so as to avoid air pockets or voids in the concrete, inasmuch as the material, while plastic, may readily flow into the cavities without the air being trapped therein.

The strips 11 have their lower edges bent back, as at 10, to form elongated open hooks to engage across the lower edges of blades or mandrels used to force the strips down into the plastic material, and a machine may be used for installing the strips or plates 7 according to the method and machine disclosed in my applications Serial Nos. 3,972 and 6,806 filed January 22, 1925 and February 4, 1925, respectively. The bent back portions 10 also anchor the strips in the concrete.

Each strip or plate 7 has a rib 11 pressed toward one side immediately below the upper edge of the strip, in order to stiffen and reinforce the strip and thereby provide a straight or regular line at the upper edge of the strip along the surface of the concrete.

By forcing the strips or plates 7 down into the concrete while it is still plastic, the strips are embedded in the concrete, thereby dividing the concrete from its upper surface downwardly to a depth equal to the width of the strips. Previous to installing the strips it is preferable that the stones or other coarse aggregate be forced down so as not to obstruct the depositing of the strips 7 in the concrete. This, with the use of plain or smooth strips, results in losing the advantages of a natural break between the upper and lower edges of the strips, and the stone, rock or other coarser aggregate do not lock the slabs together against relative vertical and horizontal displacement. With the present strips,

however, the concrete entering the cavities formed by the portions 8 will provide for the interengaging of the slabs resembling a natural break, and the concrete will develop a natural 5 break below the strips 7 so as to have a substantially natural break from its upper surface to the sub-base.

The portions 8 may be of triangular, square and other polygonal forms, and may be of various sizes, to resemble crushed stone or rock, and the apertures 9 may be punched in the strips or sheets 8, or may be formed therein by punching or tearing when pressing the portions 8 in the strips.

15 As shown in Fig. 3 the pressed portions 8' of the strip 7' are of circular and irregular curved shapes, so as to resemble pebbles or round stones, each portion 8' having an aperture 9' at its apex. With this form of strip the adjacent surfaces of the slabs will be formed to imitate a break such as occurs when using pebbles or round stones in the aggregate. Strips may thus be used 20 which correspond with the aggregate used in building the road.

25 As shown in Fig. 1 the strips 7 are employed for both longitudinal and transverse joints. The slabs 12 at the opposite sides of the longitudinal joint are tied together by the dowel or tie rods 13 embedded in the concrete and extending under the longitudinal strips 7, said rods having 30 lugs thereon or being otherwise deformed so as to be anchored in the slabs. Longitudinal dowels 14 are embedded in the slabs 12 and extend under the transverse strips 7, for holding the slabs

in alinement, said dowels being smooth and preferably treated so as to be free to slide in the slabs when the slabs contract and expand. The rods 13 and 14 may be embedded in the concrete during the pouring thereof, and the strips 7 may be deposited in the concrete subsequently over said rods.

Having thus described the invention, what is claimed as new is:—

1. A division strip to be embedded in concrete having a rib pressed therefrom immediately below its upper edge and having its lower edge bent back and extending upwardly to form an elongated open hook, said strip having pockets pressed therefrom, said pockets being distributed throughout the length of the strip between said rib and hook. 80

2. A division strip adapted to be embedded in concrete having pockets pressed therefrom to receive the plastic concrete, said pockets having air outlet apertures at the apices thereof. 90

3. A division strip adapted to be embedded in concrete having pockets pressed therefrom to receive plastic concrete, said pockets being distributed throughout the length of the strip and 100 at different distances below the upper edge of the strip, said pockets having air outlet apertures at the apices thereof.

4. A division strip adapted to be embedded in concrete, having pockets pressed therefrom to receive the plastic concrete, said pockets having air outlet apertures therein. 105
